CALCULATING MECHANISM

Charles A. Parker, Knoxville, Tenn., assignor to
 Rainey Accounting Machine Company, Inc.,
 Knoxville, Tenn., a corporation of Tennessee

Application September 15, 1949, Serial No. 115,926

24 Claims. (Cl. 235—138)

1

This invention relates to calculating machines in which register pinions are shiftable into and from mesh with calculating actuator racks for calculating and total taking operations, and wherein the tens transfer is accomplished by an additional step movement of the actuator rack. An operating member movable at each actuation through a cycle between two limit positions, in one of which it is at rest, powers stroke movement of the racks and the pinion shifting means; and there is reset mechanism for restoring to normal limit position, in the first part of each cycle of the operating member, all those racks and rack rests moved from that position in effecting transfers during the preceding cycle.

Customarily in such machines, the pinions remain in mesh at the end of each calculating stroke of the racks when the operating member comes to its position of rest at the end of its cycle. At this stage, when a transfer has been effected, one or more racks and their rests may be held out of their normal limit positions. As the reset mechanism is not actuated until the following cycle of the operating member, it is necessary in most types of machines to effect one or more blank cycles of the operating member to disengage the pinions, reset the racks and rack rests, and reengage the pinions, before a total can be taken. Elimination of enforced blank cycling has long been desired; a practical solution of the problem appears to have been reached in this invention.

Any reset mechanism of the character indicated encounters resistance which increases in magnitude from a minimum at start to a maximum at conclusion. It is required to return the racks against the force of springs which bias the racks to move into transfer receiving position. It must also return the rack rests to initial position. As the rests cannot return at a rate of movement faster than their corresponding racks, the load in moving the rests, which usually have independent bias, is added to the load imposed by return of the racks. Furthermore, the load imposes maximum resistance in the first half cycle movement of the operating member. In moving through the first half of its cycle the operating member provides the motive force for advancing the calculating actuators and their racks and for elevating type bars to printing position; all of which is against spring bias that increases in magnitude as the operating member nears the end of its first half cycle. The operating member is thus subjected to a heavy load in

2

the first part of its cycle at the very time that minimum load is most desirable.

Any reset mechanism that can be fully operated independently of the cycling operating member eliminates the need of blank cycling but is subject to the same resistance conditions encountered as when it is actuated by the operating member. The prior art has evolved spring powered means for operating the reset mechanism independently of the operating member by actuation of the total key, thus eliminating enforced blank cycling; but in all such cases the maximum effective power of the spring is exerted at the start of reset operation, when resistance of load is at the minimum; and when peak load is reached, at which time maximum spring power could best be utilized, the effective power of the spring is weakest. Maximum efficiency requires maximum spring power at maximum load, but the prior art has not shown how this can be accomplished.

In machines which operate the reset mechanism independently of the main operating member and under actuation from the total key, an objectionable characteristic is liability to incomplete operation. When an operator of the machine inadvertently pushes the total key, even though the error be caught immediately and the key be not fully moved, the mechanism has to some degree already been set in operation and, unless the proper time interval is allowed, there is likelihood of jamming or improper machine functioning and breakage of parts.

Another feature which seems to have been overlooked in prior art efforts deals with balanced operation of the mechanism. It is highly desirable that the machine function at all times with a smooth, even working of its parts. Reset mechanisms that are arranged for actuation independently of the machine's main operating member must, in the interest of efficiency, be designed to operate in as smooth a manner as that at which they operate when under the control of the operating member.

An object of the invention is to provide, in a calculating machine wherein racks and their rests are moved from normal position in effecting transfers, an improved reset mechanism for returning the parts to normal position prior to taking a total, simply by actuation of the total key; wherein the reset mechanism functions automatically by the power of spring means made effective upon the removal of a holding condition normally imposed by a movable element of the machine when the machine is at rest.

Another object is to provide, in a calculating machine having a cycling operating member and reset mechanism, power means biased to operate the reset mechanism independently of the operating member, in conjunction with limiting means movable with the operating member to regulate the speed at which the reset mechanism operates when the machine is cycled.

A further object is to provide, in a calculating machine having a reset mechanism operated normally during each cycle of the machine, means operative from the total or subtotal key to effect operation of the reset mechanism while the machine is at rest prior to cycling, in conjunction with mechanism actuated by cycling of the machine for restoring the reset mechanism to initial condition during the conclusion of each cycle.

Still another object is to provide an improved reset mechanism for restoring the racks and rack rests of a calculating machine to normal position following transfers between racks, wherein either of two restore members adapted for joint operation in unison is capable of effecting rack reset if its operation be faster than the other.

It is also an object to provide spring powered reset mechanism in which the power of a cycling operating member, moving in the second half of its cycle, is employed to energize the springs by which the reset mechanism is operated.

Other objects will be apparent from the following description in conjunction with the accompanying drawings.

In the drawings:

Fig. 1 is an elevation of the rear right hand side of a machine in which the apparatus of this invention is incorporated;

Fig. 2 is an elevation similar to Fig. 1, but with parts of Fig. 1 removed and with other parts, that are not shown in Fig. 1, added;

Fig. 3 is substantially a top plan view of the control means for actuating the reset mechanism, shown in normal position;

Fig. 4 is a plan view similar to Fig. 3, with the parts shown in actuated position;

Fig. 5 is a fragmentary elevation showing details of the racks and rack rests following a transfer between racks and with the reset mechanism in position prior to operation;

Fig. 5A is a fragmentary elevation illustrating detail of the connection between a rack and its actuator slide at the front end of the rack.

Fig. 6 is a view similar to Fig. 5, but illustrating the same parts with the reset mechanism fully operated to return the racks and rack rests to normal non-transfer-receiving position;

Fig. 7 is a vertical section through an element of the reset actuator means;

Fig. 8 is a fragmentary elevation of the structure shown in Fig. 7, but rotated ninety degrees relative thereto;

Fig. 9 is a schematic view illustrating phases of operation of the power means by which the reset mechanism is actuated.

As herein disclosed, the invention is incorporated in a calculating machine of the type shown and described in the application of Charles A. Parker, Serial No. 109,570, filed August 10, 1949, but it is not intended that it be restricted thereto. The invention is designed to function in any calculating machine that embodies actuator racks normally held by individual rests in a non-transfer-receiving position at the conclusion of a calculating operation that does not involve a transfer, and wherein the racks are spring biased

to move to transfer-receiving position. When a transfer is effected the racks receiving a transfer are given additional movement, whereby they are held in transfer-receiving position. The mechanism for resetting the racks and the rack rests normally is controlled from the operating member of the machine, and means is provided for operating the reset mechanism independently of the operating member for the purposes of total taking without the necessity of an enforced blank cycle.

As shown, the machine includes a calculating unit C, sometimes referred to as a register section, disposed between parallel side walls 40 of the calculating unit frame. These walls are secured to the base B of the machine and extend longitudinally in rear of the usual carriage, platen, and type bar assembly. The type bars are lifted to and from platen printing position, as in usual practice, by actuator slides A that move between two limit positions under the power of a main operating member OP which moves through a cycle either revolving or reciprocating. In this instance the operating member is only partly shown. The illustrated portion comprises a transverse bar at the rear end of a reciprocable frame which is driven through the agency of clutch-engaged motor means, not shown. Each actuation of the operating member effects its travel from its rearmost limit position, as shown in Figs. 1 and 4, forwardly to a limit position indicated in dotted lines in Fig. 4, and then back to its normal rest position at the conclusion of its cycle. In the normal course of operation of the machine during a calculating operation involving addition or subtraction, the register pinions are shifted to and from mesh with the racks by a driving connection with the operating member. This driving connection is herein only partly shown, as its principal components do not comprise a part of this invention. Any suitable mechanism may be employed. That portion which is here shown includes a vertical rocker post 24 that is fulcrumed intermediate its ends to oscillate in a vertical plane on a pivot stud 25 secured to a vertical support plate S appropriately fixed to the base of the machine at the right hand side of the calculating unit and in lateral spaced relation therefrom. Above its fulcrum point, the rocker post has a pivotal connection 26 with the forward end of a lever 27 which extends horizontally rearward and terminates at its rear end in an enlarged T-head 28. The arms of the head are formed with end opening keeper slots adapted to ride over and engage either of a pair of diametrically opposed studs 30 and 31 that are secured to a connector disc 29 that is mounted for rotation on an element of the calculating frame side wall 40.

The calculating machine in which this disclosed embodiment of the invention is incorporated has a dual register comprising an upper set of register pinions 60 and a similar lower set of pinions 64. These pinions are adapted to be shifted in relation to upper and lower rack sets 75. These racks include toothed upper bars 76 and lower bars 77, and are adapted for reciprocation in their respective horizontal planes by the stroke action of the actuator slides with which they are associated. The connector disc 29 has pivotal connection with a pair of oppositely directed links 33. These links at their outer ends support the sets of register pinions for bodily shifting in ac-

cordance with the throw of the links when actuated from the connector disc 29.

As illustrated in Fig. 2, the register pinions are shown in mesh with the add bars of their respective racks at the conclusion of an addition operation of the machine, wherein the racks and the operating member are in their rear positions with the operating member at rest at the conclusion of the cycle. In the normal course of add and subtract operation, when the motor clutch is engaged to cycle the operating member, the operating member moves forward and rocks the post 24 for a corresponding actuation of the lever 27 to rotate the connector disc 29. Movement of this disc carries the register pinions out of engagement with their respective racks, and they remain disengaged during the remainder of the first half of the cycle at which time the racks are differentially positioned corresponding to items indexed in the machine. Prior to return movement of the racks coincident with the second half cycle movement of the operating member, the register pinions are shifted into engagement with their respective racks so that the entered item is added or subtracted in the calculating unit in accordance with the machine controls. When the racks arrive at the end of their calculating stroke they engage rests which hold them either in a normal non-transfer-receiving position or in a transfer-receiving position, depending upon the establishment of transfers during the calculating stroke. Each rack is spring urged to move rearwardly for a further movement necessary to receive a transfer.

The rack rests of both register sets comprise thin planar rockers 82 pivoted freely on a fulcrum shaft 83 common thereto which extends transversely between supports secured on the calculating unit side walls 40. As best shown in Figs. 5 and 6, the rack engaging edge of each rocker has a relatively long straight edge face portion 84 and a short straight edge face portion 85 at an obtuse angle rearwardly from the portion 84. Both portions are tangential to the arc of swing of the rocker. Normally, with the racks at rest in rearmost position under conditions of no transfer in the register, the rockers are disposed with their short edges 85 engaged by the racks. The rockers of the respective register sets are relatively reversed, with the fulcrum shaft 83 in the upper register horizontally aligned with the bottom rack bars 77, and with the fulcrum shaft in the lower register horizontally aligned with the top rack bars 76. In each case the short edges 85 of the rockers are horizontally offset relative to the fulcrum point, so that pressure of the engaged racks under the rearward urge of their biasing springs 79 constantly biases the rockers to pivot in a direction to bring their long edges 84 to rack holding position. The rests 82 normally are held against such pivotal movement by a latch lever 86 individual to each rocker directly in rear thereof. The latch levers in each register set have one end freely pivoted on a fulcrum shaft 87 common thereto and extending transversely between the supports which mount the rocker shaft. A recess in the forward edge of each lever provides a shoulder 88 that engages over a nose 89 on the adjacent rocker when the latch lever is disposed vertically in parallel relation to the rear end of the associated rack. The end of the nose 89 is rounded off to provide ample clearance in the latch lever recess, and the latch shoulder 88 is so located that when it is engaged over the nose of the rocker the nose

is held in the same horizontally offset relation to the rocker fulcrum point as the short edge 85 of the rocker. Due to this arrangement, the pivotal bias of the rocker is transmitted through its nose portion as a vertical longitudinal thrust against the latch shoulder 88, so that the latch is held forcibly engaged also under the urge of the springs 79 when the rack contacts the rest. A relatively weak contractile spring 90 connected between the rocker and the latch lever near its fulcrum point maintains the lever in contact with the rounded edge of the rocker nose when the latch is disengaged and serves also to bias the nose of the rocker for movement out of a position in which it can engage the latch lever shoulder 88.

Fig. 5 illustrates the position of the racks and rests in a pair of adjacent racks at the conclusion of a calculating stroke in which a transfer has been effected. The transfer mechanism, which forms no part of the present invention, involves a tripping of individual latches 86. When the latch of any rack rest is tripped, the rack moves to the position indicated in Fig. 5, with its associated rest swung to present its face portion 84 for rack engagement. As the face 84 is disposed at a lesser radial distance from the fulcrum than is the short face 85, it follows that the transfer-receiving rack will be permitted a one-step further movement beyond the transferring rack, as shown. This condition continues until the racks and their rests are reset, at which time the parts assume the position shown in Fig. 6, with the rear ends of all racks engaged against the short face portions 85 of their respective rests.

When the operating member is cycled for another computing operation the register pinions are shifted to neutral disengaged position intermediate the rack bars at the beginning of the cycle and then resetting means is motivated to restore and relatch all rack rest rockers pivoted out of initial position in effecting transfers. The reset mechanism includes a fulcrum shaft 100 supported in and transversely between the side walls 40 of the calculating unit frame in both registers. The opposite ends of these shafts project outwardly through the walls 40. A vertically disposed lever 101 is pivoted intermediate its ends on each projecting end of the fulcrum shafts outwardly of the side walls. In conformity with the offset relation of the upper and lower registers, the levers 101 are correspondingly offset and are connected at their inner ends by a link 102 for movement in unison. Oscillation of the levers 101 is normally effected by means of a throw link 103 which is pivotally connected at its rear end to a cross bar 104 connected transversely between the outer end portions 105 of the levers 101 in the lower register. A second lever 106 is pivoted at its outer end on the fulcrum shaft 100 for oscillation alongside each lever 101. These levers 106 are inclined forwardly with respect to the levers 101, and each pair supports between its inner ends a transverse reset bar 107 which plays freely through clearance apertures 108 in the walls 40 forwardly of the rack rest rockers 82. A coiled contractile spring 109 is trained over a sheave 110 on the inner end of each lever 101 of the lower register and yieldingly connects the inner ends of the levers 106 and shafts 107 for movement in unison. When the levers 101 are rocked by pull of the link 103 as the operating member moves forwardly, the sheave 110 pulls the spring 109 rearwardly and correspondingly rocks the levers 106

to move the reset bars 107 against the outer front ends of the rockers 82 and return them to initial latched position.

Rack reset means is provided for operation in conjunction with the rocker reset mechanism. The rack reset in each register includes a third lever 111 also pivoted on the fulcrum shaft 109 alongside each lever 106 to oscillate in a vertical plane. The levers 111 mount between each pair a transverse reset bar 112 which plays freely through clearance apertures 113 in the walls 40 in rear of the racks. When the actuator levers 101 are rocked, the levers 111 are correspondingly pivoted through the pull of a contractile spring 114 connected between one end of each lever 111 and the cross bar 104 in the lower register set, and between one end of each lever 111 and the free end of an auxiliary link 115 in the upper register set. The other end of each link 115 is pivotally connected to the forward end of the link 102. By means of the linkage just described the rack reset bars 112 engage the rear ends of those racks moved transversely beyond the others and restore them to initial alignment with the others. Further forward propulsion of the racks is prevented by engagement of the bars 112 against the forward ends of their clearance apertures 113, which ends are vertically aligned with the short edges 85 of the rests 82 when in initial non-transfer position.

Resetting of the racks is expedited by the camming action of the rests 82 against the rear ends of the racks as the rests are swung by their own reset bars 107. Furthermore, when the rests begin resetting movement, their nose portions 89 move away from the latch levers which already are spring biased to move into engaged position; so that when the rests cease their swing the latch levers continue to move until their shoulders 88 are fully latched over the noses of the rests.

The restoring bars 107 and 112 of the reset mechanism travel through arcs in the direction of the arrows in Figures 5 and 6. It will be noted that the major portion of the travel of each bar 107 takes place as the bar is moving rearwardly to engage those rests which have been tripped out of their normal position in effecting transfers. This portion of the travel is at a relatively rapid rate, and when the bar engages the tripped rests its movement decelerates in proportion to the load imposed by the resistance of the rests in returning to normal position. It is, therefore, highly important to smooth, fast operation that maximum power be applied to the reset mechanism in that period when the reset bars encounter their maximum resistance. The reset bars 112 are moved forwardly into contact with the racks to provide a forward propulsion which returns the racks to normal non-transfer receiving position against the bias of the rack springs, just before the bars 107 have moved the rests to their fully restored position. The force of this bias increases in magnitude with forward travel of the racks, so that it is also necessary that increased power be exerted by the reset mechanism when the bars 112 encounter their maximum resistance.

In order to provide the desired increase in power, this invention includes spring motor means in combination with a system of leverage that includes a horizontal power lever 120 disposed transversely beneath the under part of the calculating unit side walls 40. The left hand end of the power lever is pivoted at 121 on a fulcrum

stud carried by the base plate of the machine, so that the lever is adapted for oscillation in a horizontal plane. In the normal position of the parts, prior to actuation of the reset mechanism, 5 the power lever is angled rearwardly to dispose its free end beneath the operating member when the operating member is in its rearmost position of rest. Intermediate its ends the power lever has a pin and slot pivot connection 122 with the forward end of a tractor link 123 which, at its rear end, has pivotal connection with a yoke 124 that is, in turn, pivotally mounted over a bolt 125 passed transversely between the convergent forward end portions of a pair of arms which comprise the throw link 103. The yoke 124 provides a flexible connection which permits limited horizontal as well as vertical swing of the tractor link with respect to the power lever and the throw link. A battery of contractile springs 128 is connected at one end to an anchor element 129 fixed on the support plate S and at its other end to the free end of a lever 130 which has a pivotal connection 131 at its other end with a portion of the power lever 120 intermediate its fulcrum and its point of attachment 122 to the tractor link. The lever 130 has a pivotal connection 132 with the free end of a shiftable fulcrum member 133 that has pivotal connection 134 at its other end to the base plate B of the machine. The pivot 132 connecting the lever 130 and the shiftable fulcrum member 133 is located adjacent the free end of the lever 130, slightly inwardly of the battery of springs. The pivot 134 for the shiftable fulcrum member is disposed rearwardly of this point in a longitudinal direction with respect to the calculating unit, so that the parts normally assume the position shown in Fig. 3, with the battery of springs 128 extended to their greatest point of expansion. A preventing means 135 on the operating member holds the power lever against movement under the bias of the springs 128 when the operating member is at rest.

When the operating member is at rest at the rear limit of its travel, as in Fig. 3, the springs 45 128 are fully extended to exert their maximum strength. The springs thus provide a constant bias urging the reset mechanism to operate. Whenever the power lever 120 is relieved of the 50 holding influence of the preventing means 135 the lever is free to swing forwardly and operate the reset mechanism through the tractor link connection 123 with the throw link 103. For the purposes of this specification, and in the 55 claims, the term "reset mechanism" includes the spring motor means 128 and the power lever 120 as well as the tractor link 123 and the throw link 103.

The preventing means 135 comprises a block 60 that is pivotally mounted on the operating member to swing in a horizontal plane. The block is adapted for vertical as well as rotary movement relative to the operating member, as shown in Fig. 7. The block is attached to the lower free end of a stem 136 that is freely rotatable as well as vertically slidable in the axial bore of a vertical cylindrical casing 137 that is screw threaded at its lower end into the body of the operating member. An expansion spring 138 between the upper end of the stem and the upper 65 closed end of the casing provides a bias constantly urging the block 135 downward toward contact with the base plate B of the machine. The block 135 has a beveled face 139 along one side edge thereof. When the operating member

is at rest, the preventing means block 135 normally is swung to a position at right angles with respect to the operating member so that it is in contact with a rounded heel flange 140 on the power lever 120. In this position the heel of the power lever contacts the block 135 at a point between the pivotal axis of the block and the forward end thereof, so that the bias of the power lever tends to rock the preventing block to swing its rear end counterclockwise, so that the power lever is free to move forwardly under the urge of its biasing springs 128. Normally this swinging movement of the preventing block 135 is resisted by blocking means 141, when the operating member is at rest at the conclusion of a cycle. This blocking means is here shown as a vertical plate having a lateral boss 142 extending from one face thereof and which pivots on a vertical pintle 143 mounted on a support 144 secured between the support plate S and the adjacent side wall 40 of the calculating unit frame. The blocking plate 141 is thus pivoted for rocking movement in a horizontal plane. The forward end of the plate has a bottom flange 145 disposed in the path of swing of the preventing member 135. A biasing spring 146 connected between the rear end portion of the blocking plate and the adjacent side wall of the calculating unit frame urges the plate to a normal position in which it blocks swinging movement of the member 135 in response to the biasing action of the power lever. An inclined finger 147 directed laterally from the rear end portion of the blocking plate provides an abutment engageable with the adjacent side wall of the calculating unit frame to limit pivotal movement of the plate and dispose it in blocking position relative to the preventing member 135.

Whenever the machine is cycled the operating member moves forward in the first half of its cycle. A slight initial portion of this movement is utilized to advance the pivotal axis of the member 135 forwardly with respect to the heel 140 on the power lever. As the operating member goes forward the axis of the member 135 passes ahead of the heel of the power lever and the heel then exerts its force against that portion of the member 135 between its pivotal axis and its rear end. This occurs at the same time that the preventing member 135 is moving with the operating member forwardly beyond control by the blocking plate 141. Accordingly, as indicated by the dotted line positions in Fig. 3, the preventing member 135 pivots around the heel of the power lever to bring its entire adjacent flat side edge into contact with the straight forward edge of the heel flange 140 on the power lever. In this position the member 135 has shifted from a preventing function to a restraining function. In its restraining function it serves to restrict forward swing of the power lever to the speed of the operating member, so that the power lever cannot swing forwardly with a snap action. Thus the reset mechanism is operated at a speed determined by the speed of the operating member. A pneumatic dash pot 148 between the intermediate lever 130 and a point of attachment on the base plate of the machine provides a brake which retards action of the leverage so that it cannot be operated too rapidly.

As soon as the operating frame has moved forward to the point at which the influence of the member 135 changes from prevention to restraint, the full force of the springs 128 pulls on the end of the intermediate lever 130 to swing the shift-

able fulcrum 132 counterclockwise in a forward arc of movement that is correspondingly transmitted to the power lever 120 and through the tractor link 123 to the throw link 103 for operation of the reset mechanism. When the operating member arrives at its forward limit, as shown in dotted line position in Fig. 4, the reset mechanism will have been fully operated to move the restore bars 107 and 112 to the positions indicated in Fig. 6, with the racks and rack rests restored to normal non-transfer-receiving position. When the operating member moves rearwardly in the second half of its cycle, the member 135 carries back with it the power lever 120. In its return movement the member 135 swings reversely around the nose flange of the power lever back to its original position into engagement with the blocking plate. In this return movement the operating member, acting through the member 135, provides the motive force for returning the reset mechanism to its original position against the bias of the springs 128. This operation returns the reset bars 107 and 112 to their normal free position, as shown in Fig. 5. The maximum load on the reset mechanism occurs during the last portion of its operation, when the bars 107 and 112 engage the rack rests and the racks. This point of engagement occurs in approximately the third quarter of the arc of movement of the reset bars, and the resistance of the load increases to a maximum when the reset is fully operated. Accordingly, the greatest load to be overcome by contraction of the springs 128 occurs during the period at which the springs are nearing their weakest state. The provision of the intermediate lever 130 in conjunction with the swinging fulcrum member 133 provides a power amplifying leverage which increases the effective power of the springs as their contracting power decreases, so that the effective power of the springs actually is at maximum when the strength of the springs is weakest. This operation is readily understandable from the schematic representation of Fig. 9. In this view the respective starting positions of the power lever, the intermediate lever, and the fulcrum connecting the intermediate lever and the shiftable fulcrum member are indicated by their respective reference characters hereinbefore given. The suffix *a* denotes the positions of the parts at the conclusion of the first quarter of the arc of movement; the suffix *b* indicates the position at the end of the second quarter; the suffix *c* indicates the position at the end of the third quarter, and the suffix *d* indicates final position at the conclusion of the operating movement through the last quarter. Curved line *x*—*x* denotes the path of travel of the shifting fulcrum 132, and the points *x*'—*y* denote the direction of force exerted by the springs 128. It will be seen that during the first 25% of operation of the reset mechanism the springs contract through approximately 6% of their contracting movement, when they are strongest. During the second 25% of operation of the reset mechanism the springs contract through approximately 17% of their movement. During the third 25% of operating movement of the reset mechanism the springs contract through approximately 29% of their movement. During the last 25% of operation of the reset mechanism the springs are contracting through approximately 43% of their movement. By this arrangement, the greatest contracting movement of the springs takes place in the final quarter of operation of the reset mechanism. Although the

11

springs are at their weakest strength during this final portion of movement, the amplifying power of the leverage actually increases the effective force of the springs so that their effective force for purposes of operating the reset mechanism is greatest in the last quarter of its operation.

This invention incorporates means for effecting operation of the reset mechanism independently of movement of the operating member, thereby eliminating the necessity of an enforced blank cycle prior to taking a total. This means includes a control element 149, here shown as a rod axially movable by operation of the total or subtotal key, and which has rigidly secured thereon a fixed cam 150. The cam has a tip 151 and an inclined edge 152. In the normal position of parts, prior to an actuation of the total key, the inclined edge of the cam is engaged behind a flange 153 on the short arm 154 of a bell crank lever 155. The bell crank lever is disposed horizontally and is fulcrumed on a stud shaft 156 that is anchored in an element 157 of the machine frame. An expansion spring 158 surrounds the fulcrum shaft between the frame element 157 and a retainer nut 159 on the lower end of the shaft and maintains the bell crank lever in proper horizontal position. A long arm 160 of the bell crank lever has pivotal connection 161 at its outer end with a throw link 162 which is in operative connection with a lateral stud 163 on the upper end of the rocker post 24. When the total key rod 149 is shifted by actuation of the total key, the rod moves rearwardly, to the right with respect to Fig. 3, whereby the inclined edge 152 of the cam, acting against the rear of the flange 153 on the bell crank rocker, rocks the bell crank lever in a counterclockwise direction. This movement of the bell crank lever is transmitted through the link 162 to actuate the rocker post 24 to the dotted line position of Fig. 1, to disengage the register pinions from mesh with their racks. When the cam 150 has advanced to the point at which its inclined edge 152 clears the flange 153 of the bell crank lever, the bell crank lever is conditioned for return movement to engage its flange 153 behind a shoulder 164 on the cam, as shown in Fig. 4. This engagement of the flange and cam shoulder latches the rod 149 in its fully actuated position.

As the total rod 149 moves rearwardly to cam the bell crank lever 155 for disengagement of the register pinions it carries with it an upwardly and laterally directed actuator 165 that is fixedly secured to the shank of the total rod. The actuator carries an arm 166 pivoted thereon at 167 that is retained in longitudinal alignment with the actuator by means of a contractile spring 168 connected between a flange 169 on the arm and a stud 170 on the actuator. This arrangement permits a counterclockwise movement of the arm 166 relative to the actuator against the force of the biasing spring. As the actuator 165 moves rearwardly with the rod 149, its arm 166 contacts a lateral stud 171 on a horizontally disposed interponent lever 172. The forward end of the interponent 172 is enlarged to provide a head 173 having a closed end slot 174 that is received over a lateral stud 175 on the long arm 160 of the bell crank lever 155. The stud and slot connection pulls the interponent forwardly when the bell crank lever is rocked to disengage the register pinions. In moving forward, the stud 171 on the interponent cams the pivoted arm 166 to rock against the tension of its spring 168. Forward movement of the interponent advances a shoul-

12

dered recess 176 in the edge of the interponent adjacent its rear end. In its advanced position the recess is adapted to engage the upper end portion 177 of a rod 178. The upper portion of this rod is provided with a laterally directed terminal 179 which overlies the interponent. A contractile spring 180 between the support plate S and the shank of the interponent normally biases the interponent to move laterally for engagement of the upper end of the rod 177 in the recess 176.

As soon as the inclined edge 152 on the total rod cam 150 passes forwardly of the bell crank lever flange 153, the force of the tensioned spring 168 acts to rock the arm 166 rearwardly to carry with it the interponent 172. This movement of the interponent exerts a pull on the bell crank lever stud 175 and this pull snaps the bell crank lever back to a position in which its flange 153 latches behind the shoulder 164 of the total rod cam, returning link 162 to position shown in Fig. 1, where stud 163 can oscillate with rocker post 24, in the slot of link 162. Further movement of the bell crank lever is prevented by a retaining flange 161 on the body of the cam. By this means the actuated total key rod 149 is latched in fully actuated position and the total key is held latched until suitable means, not shown, actuated by the operating member when it moves rearward in its last half cycle, releases the latch by a vertical lift of lever arm 154 and flange 153 against the bias of its spring 158, so that the total key may be returned to its non-actuated position.

When the interponent 172 shifts rearwardly under the pull of the spring 168 the shoulder at the forward edge of the recess 176 correspondingly effects a bodily rearward shift of the rod 178. A guide member 182, attached to a support element 183 of the machine, is formed with a pair of spaced parallel arms 184 which straddle the rod and determine the extent of its shifting movement. The lower end of the rod 178 is rigidly secured to the release lever 187. This release lever is inclined rearwardly and downwardly and is pivoted at its upper end as at 188 to the support 183. By this arrangement, when the rod 178 is rocked rearwardly it rocks the release lever 187 downwardly to lower its rear end extension, a laterally directed rod 189, below the plane of the rear portion of the blocking plate 141. The extension 189 normally abuts the blocking plate 141 when the release lever is in its normal upper position, as in Figs. 1 and 3. In this upper position the rod holds the blocking plate 141 against pivotal movement under the bias of the preventing member 135 which, as previously explained, is itself biased to swing by its engagement with the heel flange 140 on the power lever 120. When the release lever 187 is rocked downwardly to clear the blocking plate 141, this plate is free to swing under the force of the preventing member 135, whereupon the preventing member swings, as previously described, to release the heel of the power lever 120 for operation of the reset mechanism.

When the heel of the power lever clears the preventing member 135, a relatively weak contractile spring 190 Fig. 8 swings the preventing member out of its transverse position and into alignment with the operating member upon which it is mounted. When in this position, the bevel face 139 of the preventing member is presented forwardly. As the operating member moves into its forward limit position toward the end of the first half cycle, the bevel 139 rides up

a complementary inclined face portion 191 on the rear edge of the heel of the power lever. The preventing member thereupon rides up and over the heel of the power lever and drops into position for engagement with the forward edge portion of the heel as shown in dotted line position in Fig. 4. When in this position, the flat side edge of the preventing member contacts the heel of the power lever so that when the operating member moves rearwardly in the second half of its cycle the preventing member carries the power lever back with it to return the reset mechanism to its initial condition. In its return movement the member 135 swings around the nose of the power lever, so that in the last portion of the second half cycle movement of the operating member, just before it comes to rest, the pivotal axis of the member 135 passes rearwardly of the heel flange of the power lever, whereupon the member 135 is swung to its preventing position under the control of the blocking plate 141 which is held against swinging movement by contact with the end of laterally directed rod 189.

The power lever has associated therewith a motor clutch trip lever 192 that is pivoted on the fulcrum 121 of the power lever. A contractile spring 193 connected between the shank of the power lever and the rear end of the clutch trip lever provides a yieldable connection urging the clutch trip lever to follow movement of the power lever when the power lever is swung forwardly in the operation of the reset mechanism. When the power lever reaches full operated position, as in Fig. 4, the trip lever 192 will have been moved to the point at which the motor clutch, not shown, is tripped to effect a cycle of the operating member. When the operating member nears the rear limit of its travel on the return stroke it is highly desirable that it be relieved of load wherever possible, so that the motor clutch may be disengaged just slightly before the operating member comes to rest. This relief is effected in this invention by the reverse action of the springs and the amplifying power leverage. The amplifying leverage operates reversely when the power lever returns to normal position so that the heel of the power lever bears only lightly against the preventing member 135, and the power lever is not given any further rearward movement when the preventing member 135 has swung around the heel 140 and moved rearwardly in contact with flange 145 of blocking plate 141. There is, accordingly, only a very slight friction between the heel of the power lever and the preventing member 135 and no further movement of the power lever 120, which materially lightens the load on the operating member when it is moving into its extreme rear limit position.

It will be apparent that the operation of the interponent 172 to disengage the rod 189 from the blocking plate 141 is under the control of the bell crank latch lever 155. The interponent cannot move rearwardly to effect release of the plate 141 until the bell crank lever is in latched position. It is therefore necessary that the total key rod 149 be moved to its full operated position and that it be latched in that position before the reset mechanism can operate.

When the bell crank lever 155 is in position holding the rod 149 latched, the interponent lever 172 is held in its rear position, as in Fig. 4, with the upper portion of the rod 178 engaged behind the shoulder of the recess 176. Means is provided for camming the interponent laterally

to release the rod 178 when the operating member goes forward. This means comprises a horizontal lever 194 pivoted at one end to a block 195 secured on the support S. The lever is biased to swing forwardly by the pull of a contractile spring 196 connected between the lever and guide arm 184. The lever 194 underlies the rear end of the interponent 172 and carries an upstanding stud 197 which is adapted to engage an inclined cam edge 198 of the interponent. A post 199 on the operating member engages the free end of the lever 194 and holds it against forward swing while the operating member is at rest. As the operating member goes forward the post 199 moves ahead of the end of lever 194, which then swings under the pull of its spring to engage its stud 197 against the cam 198; whereupon the interponent is shifted laterally to release the upper portion 177 of the rod 178. Upon release, the rod returns to normal position under pull of a spring 186 connected between the rod 178 and the post 183 at a point well above the pivot of the release lever 187. Return movement of the rod 178 lifts the release lever into position to reengage the blocking plate 141. When the operating member nears the end of its back stroke the post 199 reengages the end of the lever 194 and returns the lever to its normal position with the stud 197 disengaged from the interponent cam 198.

Operation of the reset mechanism by actuation of the total key is effected independently of operating member control. The reset operation is accomplished before the motor clutch is tripped to cycle the operating member. The motive power of the operating member returning in its second half cycle is utilized to restore the reset mechanism to its initial condition and also to return the total key control mechanism to its original condition. When the machine is cycled in taking a total, forward movement of the operating member rocks the post 24 to reengage the register pinions with their racks just before the racks begin their forward stroke from their reset position.

This invention also includes means whereby, in the event of lagging or failure of the springs 128 for any reason, the reset mechanism is operated by a positive drive from the operating member as it arrives at the end of its forward stroke. This means comprises a link 200 attached at its forward end to the operating member and extending rearwardly over the yoke 124 and the cross bar 104. A pin 201 on the yoke plays in a longitudinal closed end slot 202 in the link. When the operating member goes forward, the rear end of the slot normally engages the yoke pin 201 as the operating member nears its forward limit position and functions in conjunction with the power lever 120 to operate the reset mechanism. If for any reason the power lever lags or fails to move, the rear end of the link slot 202 picks up the yoke pin at whatever position it occupies when reached, and propels it forwardly to operate the reset mechanism. This arrangement insures operation of the reset mechanism at each cycle of the operating member. It provides two instrumentalities, acting separately or in unison, for operating the reset mechanism, so that whichever of the two works the faster provides the operating power.

From the detailed description above given, it will be evident that this invention broadly provides a means capable of actuation by the total or sub-total key to effect resetting of racks and

15

rack rests prior to a cycle of the operating member. The reset mechanism, although adapted for positive operation by the operating member, is powered to operate independently of control by the operating member, and is biased to operate at all times when the operating member is at rest. Preventing means normally holds the reset mechanism against operation. The holding influence of the preventing means is removable either by cycling the operating member or by actuating the total key prior to a cycle of the operating member. The preventing means is movable on and with the operating member, and when the operating member is at rest the preventing means is engaged with an element of the reset mechanism that is biased to move the preventing means out of its holding position. A blocking means under the control of the total key normally blocks releasing movement of the preventing means while the operating member is at rest. When the reset mechanism is operated by control from the operating member the preventing means has a dual function: it functions first to hold the reset mechanism against operation until the operating member has accomplished an initial portion of its movement, and its functions thereafter during the first half cycle movement of the operating member as a restraining means which limits operation of the reset mechanism to the speed of operation of the operating member. Following either mode of operation of the reset mechanism, restoration of the reset mechanism to initial condition is accomplished by the motive power of the operating member returning through the second half of its cycle.

A broad phase of the reset mechanism includes two restoring elements, the bars 107 and 112, that are adapted for operation in unison. Either of these elements alone is capable of returning the racks to reset position; and therefore the rack resetting is taken over by whichever of the two moves the faster, thus insuring maximum speed in resetting the racks.

In a further aspect the invention broadly provides a means for utilizing the energy of the operating member moving in its return stroke during its second half cycle to restore the power of the springs which motor the reset mechanism for operation during the forward stroke of the operating member in its first half cycle. In calculating machines in which the type bars, register accumulator actuators, and racks are moved and positioned by springs which are energized by the operating member in the first half of its cycle, it is desirable to use the power of the operating member in the second half of its cycle to energize the reset mechanism. This effects a more even distribution of the motor power driving the operating member, so that it is substantially uniform throughout the full cycle.

The invention also provides broadly an arrangement in which a power lever, driven independently of the machine operating member and movable in a cycle corresponding to the cycle of the operating member, actuates a rack reset mechanism during a part of its first half cycle movement, and is then adapted for positive drive by the operating member during the remainder of its first half cycle to actuate a reset mechanism which restores the rack rests to initial position. The rest reset thus takes place jointly with and following the rack reset.

In another broad phase, the invention provides

a power amplifying system in which a spring motored work-performing member is increased in power as it decelerates in movement with increase in load. It provides means for increasing the effective power of a tensioned spring coincident with decrease in its operating power as it returns to a normal condition of less tension.

The term "tens transfer" is widely used by the industry and herein to indicate transfer whether carried out at the zero or ten position or whether carried out at other positions such as the eight or twelve position.

Although the present invention has been described in conjunction with preferred embodiments, it is to be understood that modifications and variations may be resorted to without departing from the spirit and scope of the invention, as those skilled in the art will readily understand. Such modifications and variations are considered to be within the purview and scope of the invention and appended claims.

I claim:

1. In a calculating machine, a spring operated tens transfer reset mechanism for returning to normal position all racks and rack rests moved therefrom in effecting transfers, an operating member for the machine, said reset mechanism being adapted for normal operation under control of the operating member, a control element movable to an actuated position to condition the machine for taking a total, means for latching said control element in actuated position, and means controlled by the latching means to effect operation of the reset mechanism independently of the operating member.

2. In a calculating machine having tens transfer elements and a tens transfer reset mechanism for restoring the tens transfer elements when operated, a cycling operating member, means operatively engaging the tens transfer mechanism to bias same to operate independently of the operating member, preventing means on the operating member normally holding the reset mechanism against operation while the operating member is at rest, said preventing means movable with the operating member and becoming ineffective during the first part of the cycle of the operating member to release the tens transfer reset mechanism for operation and becoming effective during the last portion of the cycle of the operating member to cause return of the tens transfer reset mechanism to its original biased condition.

3. In a calculating machine having tens transfer elements operative to effect tens transfer during a cycle of operation and tens transfer reset mechanism operatively engaging the tens transfer elements to restore same when operated, a cycling operating member, means biasing the tens transfer reset mechanism to operate independently of the operating member, preventing means carried by the operating member and movable thereon, said preventing means contacting an element of the reset mechanism when the operating member is at rest whereby to hold the reset mechanism against operation, said preventing means being movable by the biasing force of the reset mechanism to release the contacting reset element for operation of the reset mechanism upon initial movement of the operating member from its position of rest, means normally engageable with said preventing means to block its reset release movement, and control means operative to remove the blocking means relative to said preventing means independent of

75

movement of the cycling member from its position of rest.

4. In a calculating machine having racks movable from a normal rest position in effecting a transfer, an operating member movable through a cycle, and reset mechanism for restoring to normal position all racks moved therefrom in a transfer; said reset mechanism being adapted for actuation under control of the operating member on each cycle thereof, a control element movable to condition the machine for a total taking operation, and means operative from said control element upon movement thereof to effect actuation of the reset mechanism independently of operating member control.

5. In a calculating machine, an operating member movable through a cycle upon each operation of the machine, a tens transfer reset mechanism biased to operate, means on the operating member normally blocking operation of the tens transfer reset mechanism while the operating member is at rest in its normal position, other means independent of the operating member for rendering said blocking means ineffective to enable the tens transfer reset mechanism to carry out its tens transfer resetting operations.

6. In a calculating machine, an operating member movable through a cycle upon each operation of the machine, a tens transfer reset mechanism biased to operate, means movably mounted on said operating member for operative engagement with said tens transfer reset mechanism to block operation thereof when said operating member is in normal position of rest, said means becoming inoperative upon movement of said operating member through the first portion of its operating cycle, and other means for rendering said blocking means ineffective independent of the operating member.

7. In a calculating machine, a cycling operating member, tens transfer reset mechanism, spring means constantly urging the reset mechanism to operate while the operating member is in normal position of adjustment, means normally holding the tens transfer reset mechanism against operation while the operating member is in normal position of adjustment, said holding means becoming ineffective during the first portion of the cycle of the operating member and other means for rendering said holding means ineffective independent of said operating member to permit operation of said tens transfer reset mechanism when the operating member is in normal position.

8. In a calculating machine, a cycling operating member, tens transfer reset mechanism, spring means constantly urging the reset mechanism to operate when in the normal position of adjustment, means normally holding the reset mechanism against operation when the cycling member is in normal position of adjustment, said holding means becoming ineffective upon operation of the cycling member, other means for rendering said holding means ineffective independent of said operating member to permit operation of said tens transfer reset mechanism, and means under the control of the operating member to return the spring operated tens transfer reset mechanism to initial condition during the latter portion of its cycle independent of the manner in which the tens transfer reset mechanism was released from its blocked position.

9. In a calculating machine, an operating member movable through a cycle of operation upon each operation of the machine, a tens trans-

fer reset mechanism biased to operate, means mounted on the operating member operatively engaging said tens transfer reset mechanism to block operation thereof when the operating member is at rest in its normal position, said blocking means being shiftable with said operating member to release said tens transfer reset mechanism during initial movement of the operating member through its cycle of operations.

10. In a calculating machine, an operating member movable through a cycle upon each operation of the machine, tens transfer reset mechanism biased to operate, means mounted on the operating member for relative movement and positioned thereon operatively to engage said tens transfer reset mechanism to block operation thereof when said operating member is at rest in its normal position, said blocking means moving out of blocking position during initial movement of the operating member through its cycle of operation to release said tens transfer reset mechanism for operation.

11. In a calculating machine, an operating member movable through a cycle upon each operation of the machine, tens transfer reset mechanism biased to operate, means pivotally mounted on the operating member operatively engaging said tens transfer reset mechanism for blocking movement thereof when said operating member is at rest in its normal position, said blocking means pivoting out of blocking position to release said tens transfer reset mechanism during initial movement of the operating member through its cycle of operation to release said tens transfer reset mechanism for operation.

12. In a calculating machine, an operating member movable through a cycle upon each operation of the machine, tens transfer reset mechanism biased to operate, means pivotally mounted on the operating member operatively engaging said tens transfer reset mechanism for blocking movement thereof when said operating member is at rest in its normal position, said blocking means pivoting to engage said tens transfer reset mechanism from another direction during initial movement of the operating member to release said tens transfer reset mechanism for operation and control movement thereof.

13. In a calculating machine, an operating member movable through a cycle upon each operation of the machine, a tens transfer reset mechanism including a reset lever spring urged to operate, a pawl pivotally mounted on the operating member for operative engagement with the end portion of said lever to block operation thereof when said operating member is in normal position of rest, said pawl shifting out of blocking position upon movement of the operating member in an initial portion of its operating cycle to release said lever for operation of said tens transfer reset mechanism, the pawl continuing operatively to engage the lever for control of the movement of the reset mechanism and return thereof to starting position during return movement of the operating member.

14. In a calculating machine, an operating member movable through a cycle upon each operation of the machine, a tens transfer reset mechanism spring biased to operate, means pivotally mounted on the operating member operatively engaging the tens transfer reset mechanism for blocking movement thereof when the operating member is in normal position of rest, said blocking means pivoting out of blocking position during initial movement of the operating member

to release said tens transfer mechanism for operation, and separate means for pivoting said blocking means out of blocking position while the operating member remains in position of rest to release said tens transfer mechanism in advance of movement of the operating member.

15. In a calculating machine, an operating member movable through a cycle upon each operation of the machine, a tens transfer reset mechanism spring biased to operate, a blocking member mounted for movement relative to the operating member and positioned operatively to engage the tens transfer reset mechanism to prevent operation thereof when the operating member is in normal position of rest, means holding said blocking member in position to block movement of the tens transfer reset mechanism, means pivoting said blocking member out of position for blocking said tens transfer reset mechanism during initial movement of the operating member in its cycle of operation and separate means for rendering said holding means ineffective to release said blocking means independent of movement of said operating member whereby the tens transfer reset mechanism is released for operation.

16. In a calculating machine, an operating member movable through a cycle upon each operation of the machine, a tens transfer reset mechanism spring biased to operate, a blocking member mounted on the operating member for movement relative thereto and in position operatively to engage the tens transfer reset mechanism for blocking operation thereof when the operating member is in normal position of rest, means holding said blocking member in position to resist movement of said tens transfer reset mechanism when the operating member is in normal position of rest, said holding means becoming ineffective when said operating member moves out of position of rest during an initial portion of its operating cycle to release said tens transfer reset mechanism for operation, and means for rendering said holding means ineffective whereby the blocking means is released to permit operation of said tens transfer reset mechanism independent of movement of the operating member.

17. In a calculating machine, an operating member movable through a cycle upon each operation of the machine, a tens transfer reset mechanism spring biased to operate, a blocking member movably mounted on the operating member, means holding said blocking member in position operatively to engage the tens transfer reset mechanism to block operation thereof when the operating member is in normal position of rest, said holding means becoming ineffective upon movement of the operating member from its position of rest during an initial portion of its operating cycle whereby the blocking member is shifted out of blocking position responsive to the bias of the tens transfer reset mechanism to permit operation thereof, and other means for rendering said holding means ineffective independent of said operating member to release said tens transfer reset mechanism for operation.

18. In a calculating machine, an operating member movable through a cycle upon each operation of the machine, a tens transfer reset mechanism spring biased to operate, a blocking pawl pivotally mounted on the operating member, means holding said pawl in position operatively to engage a portion offset from its pivot with

the tens transfer reset mechanism to block operation thereof when said operating member is in normal position of rest, said holding means becoming ineffective upon movement of said operating member from its normal position of rest whereby the blocking pawl is pivoted out of blocking position responsive to the biased tens transfer reset mechanism to permit operation thereof, and other means for rendering said holding means ineffective independent of said operating member to permit pivotal movement of said pawl out of blocking position to release said tens transfer mechanism for operation.

19. A calculating machine as claimed in claim 18 in which said pawl remains in the path of the tens transfer reset mechanism when pivoted out of blocking position upon movement of operating member in its cycle of operation thereby to control movement of the biased tens transfer reset mechanism during the first half portion of its cycle.

20. A calculating machine as claimed in claim 18 in which the pawl pivots to one side in the path of the biased tens transfer reset mechanism upon release responsive to movement of the operating member from its position of rest and is pivoted to the other side thereof responsive to the offset engagement between the pawl and the biased tens transfer reset mechanism when released from means independent of movement of the operating member.

21. A calculating machine as claimed in claim 18 in which the pawl becomes positioned operatively to engage the tens transfer reset mechanism during the return portion of the cycle of the operating member no matter how it is released to actuate the tens transfer mechanism to its original biased position with the pawl in its original blocking engagement therewith.

22. In a calculating machine, an operating member movable through a cycle upon each operation of the machine, tens transfer reset mechanism biased to operate, means on the operating member shiftable between a position blocking operation of the tens transfer reset mechanism when the operating member is in normal position of rest and positions releasing said tens transfer reset mechanism for operation, a holder shiftable between position for holding the blocking member in blocking position and for releasing said blocking member for shifting movement to position releasing said tens transfer reset mechanism for operation, a control member shiftable to a position for conditioning the machine for total taking, latching mechanism in operative engagement with said control member to lock same when actuated to position for total taking, and trip mechanism operated by said control member when locked in position for total taking for shifting said holder to position for release of said means on the operating member from its blocking position.

23. A calculating machine as claimed in claim 22 in which the means for locking the control member when shifted into position for total taking comprises a cam member shiftable with said control member and having a recess to one side therein, a pivoted lever having a locking pawl urged in a direction into contact with said cam member whereby the lever is cammed in the other direction until the control member is shifted to position for total taking whereby the slotted portion becomes aligned with said pawl to permit entrance thereof to prevent return of the control member.

24. A calculating machine as claimed in claim 22, in which the trip mechanism comprises a yieldable lever secured to the control member for shifting movement therewith, an interponent movable to control operation of the holder, means responsive to movement of the control member to position for total taking for releasing the interponent for shifting movement between untripped and tripped position of the holder member, and means responsive to shifting movement of the lever for actuating said interponent towards tripped position when the control member is locked in position for total taking.
